EDGAR F. HEISER, OF KINGSTON, MISSOURI.

CYLINDER-REBORING MECHANISM.

1,231,347.

Specification of Letters Patent. Patented June 26, 1917.

Application filed May 17, 1916. Serial No. 98,143

To all whom it may concern:

Be it known that I, EDGAR F. HEISER, a citizen of the United States, residing at Kingston, in the county of Caldwell and State of Missouri, have invented certain new and useful Improvements in Cylinder-Reboring Mechanism, of which the following is a full and exact specification.

The present invention relates to improvements in metal-working machinery, and more particularly to devices for use in the re-boring of metal cylinders, a device of which general character is illustrated and described in my co-pending application 15 Serial No. 30,105, filed May 24, 1915.

One of the special objects of the present invention is to devise an improved tool-holding construction for machines doing this class of work, whereby the tool may be conveniently adjusted and its adjustment be maintained for successive boring operations, if desired.

It is a further object of the invention to provide a tool-holding construction of such 25 a character that the position of the tool may be so changed as to facilitate the grinding or sharpening of the tool simply by continued rotation of the tool-carrying shaft with the tool in engagement with the inner 30 face of the cylinder.

Further features of improvement reside in the new mode of grinding operation for sharpening tools as related to the practice of the invention, as hereinafter set forth.

With these various objects in view, the 35 invention will now be described with reference to the accompanying drawing illustrating one form of embodiment of the invention and mode of practising the same, after 40 which those features of the present improvements deemed to be novel will be severally set forth and defined in the appended claims.

In the drawing—

Figure 1 is a transverse section through 45 a cylinder and re-boring mechanism therefor, the section being taken through the tool-carrying portion of the boring shaft;

Fig. 2 is a similar view on a smaller scale, showing the tool-holder in plan and the tool 50 shifted into position for grinding or sharpening the same;

Fig. 3 is a detail illustrating the position of the tool with relation to the cylinder when modifying the contour of the cutting edge; and

Fig. 4 is a fragmentary plan view of the

cutting portion of the tool illustrating the outline of the cutting edge as modified.

Referring to the drawing in detail, the boring or tool-carrying shaft 2 of the re-boring mechanism is adapted to be mounted axially within the bore of the cylinder 4, and operated to feed the shaft axially as the cutting operation proceeds, all as in my co-pending application above identified, and the details of said cutting and feeding construction are not herein illustrated since the same form no essential part of the present improvements. As in my previous construction, the tool-carrying shaft 2 is provided 60 with a transverse opening 6, extending at right angles to the axis of the shaft 2, but in the present construction the axis of said opening, instead of intersecting the axis of the shaft, is located eccentrically of said shaft, so that the axis of the tool-holder 8, which is mounted in said opening, will also occupy a position eccentric to the shaft. 70 This tool-holder is provided with an axial opening 10 within which to mount the cutting tool 12. The holder 8 is also provided with the axial adjusting screw 14 in abutting relation with one end of the tool 12, whereby the latter may be adjusted axially within the opening 10. The tool is clamped 75 in adjusted position by means of the screw 16 mounted in the enlarged head portion of the holder 8, and the latter is clamped within the shaft opening 6 by the screw 18 carried by the shaft 2 in position to engage the 80 shank of said holder.

By means of this tool holding arrangement it will be apparent that the tool can be adjusted within the holder and the latter removed and re-applied to the shaft without 95 disturbing the adjustment of the tool as first made, and which is a distinct advantage where the same approximate adjustment of the tool is desired to be maintained for successive bore operations.

Figure 1 illustrates the position of the parts during the cutting or re-boring operation. The cutting edge 20 of the tool engages and cuts the interior face of the cylinder 4 as the shaft 2 is rotated in the direction of the arrow in said figure, the cutting end or nose of the tool being formed to leave a slight clearance space 22 behind said cutting edge. By continued use of the tool the nose portion will be gradually worn 105 down as indicated on an exaggerated scale by the dotted line 24, so that it becomes 110

necessary to sharpen the same, and this operation in the present case is accomplished in the following manner.

Either the tool holder 8 is rotated through 5 approximately 180 degrees within the opening 6 or the tool 12 is rotated within the holder to the same extent, as shown in Fig. 2, and clamped in its new position relative to the shaft 2. A portion of the interior face 10 of the cylinder 4 is treated with a suitable abrasive material such as emery paste, and the shaft 2 rotated a few times with the parts arranged as just described, resulting in grinding of the tool down to the dotted line 15 26 (the ground-away portion being represented on an exaggerated scale) so that the line 24 represents the new end face of the tool; and when the tool is restored to operative position as in Fig. 1 a newly sharpened 20 edge 20 is presented to the interior face of the cylinder with the proper clearance space 22 at the rear of the cutting points. This result, viz., the sharpening of the tool by reversing its position and continuing the rotation of the boring shaft, is obtained by 25 virtue of the peculiar mounting of the tool eccentrically with relation to the shaft 2.

It is also desirable, for the purpose of preventing any scoring of the interior face 30 of the cylinder in the process of re-boring, that the cutting edge 20 of the tool 12 be rounded off slightly at the rear end of said edge,—that is, at the rear end thereof with reference to the direction of the feeding 35 movement of the tool axially of the cylinder. This result is accomplished by shifting the tool slightly about its longitudinal axis, either by rotating the tool within its socket or by simply rotating the holder 40 within the shaft opening 6 to the required extent, thereby bringing the tool in the relation to the cylinder somewhat as illustrated in Fig. 3; and then completing the sharpening operation by one or two final 45 turns of the boring shaft with the tool in engagement with the abrasive surface of the cylinder. Since this shifting of the tool into the position shown in Fig. 3 necessarily swings one corner of the cutting end of the 50 tool away from the interior face of the cylinder, whereas the opposite corner at the opposite end of the cutting edge is swung directly into said face, the latter corner is of course rounded off as indicated at 55 28 in Fig. 4.

It will thus be apparent that an extremely simple and efficient means has been devised for carrying out the aforesaid objects of the invention, and while the foregoing represents what is now deemed to constitute the preferred form of embodiment of the invention and mode of practising the same, the right is reserved to all such formal changes and modifications as may fairly fall 60 within the scope of the appended claims.

Claims:

1. In a cutting mechanism, the combination with a rotary tool-carrying shaft provided with an eccentric transverse opening, of a tool mounted on said shaft and within said opening and adapted to be rotated into different angular positions therein with reference to the axis of said opening. 70

2. In a cutting mechanism, the combination with a rotary tool-carrying shaft, of a cutting tool carried by said shaft, said tool being rotatable into different positions about an axis extending through the cutting end of the tool at right angles to said shaft and eccentric thereto. 75

3. In a cylinder-reboring mechanism, the combination with a rotary tool-carrying shaft provided with a transverse opening having its axis at right angles to said shaft and eccentric thereto, of a cutting tool carried by said shaft within said opening and adapted to be clamped in various angular positions with reference to the axis of said opening. 80

4. The method of sharpening the tools of cylinder reborining devices which consists in applying an abrasive to a portion of the interior face of the cylinder, mounting the tool on the boring shaft with the axis of the tool at right angles to the shaft and eccentric thereto, and rotating said shaft with the tool in engagement with said abrasive surface but shifted about its axis out of normal cutting position. 90

5. The method of sharpening the tools of cylinder reborining devices which consists in applying an abrasive to a portion of the interior face of the cylinder, mounting the tool on the boring shaft with the axis of the tool at right angles to the shaft and eccentric thereto, rotating said shaft with the tool shifted about its axis to a position the reverse of its normal cutting position, and thereafter rotating the shaft with the tool shifted about its axis to a position intermediate said normal and reverse positions for slightly rounding off a portion of the tool's cutting edge. 100

6. The method of sharpening the tools of cylinder reborining devices which consists in applying an abrasive to a portion of the interior face of the cylinder, mounting the tool on the boring shaft for adjustment about an axis at right angles to the shaft and eccentric thereto, and rotating said shaft with the tool in engagement with said abrasive surface but shifted about said axis out of normal cutting position. 115

7. In a cutting mechanism, the combination with a tool-carrying shaft, of a tool-holder mounted detachably on said shaft and provided with a tool opening or socket extending at right angles to said shaft, a cutting tool mounted within said opening or socket, and means for adjusting the tool 120 125 130

within said socket and for clamping the same in adjusted position.

8. In a cutting mechanism, the combination with a rotary tool-carrying shaft provided with a transverse opening having its axis at right angles to said shaft, of a tool holder mounted detachably on said shaft within said opening and adapted to be clamped in various angular positions with

reference to the axis of the opening, said holder being provided with a tool socket extending at right angles to said shaft, a cutting tool mounted within said socket, and means for adjusting said tool within said socket and for clamping the same in adjusted position.

E. F. HEISER.
